UNITED STATES PATENT OFFICE.

HENRY O. WHITE, OF ALEXIS, ILLINOIS.

ENGINE.

Application filed July 26, 1923. Serial No. 653,929.

To all whom it may concern:

Be it known that I, HENRY O. WHITE, a citizen of the United States, residing at Alexis, in county of Warren and State of Illinois, have invented certain new and useful Improvements in Engines, of which the following is a specification.

This invention relates to steam or other motive fluid driven engines, more particularly to an improved engine cylinder and valve controlling mechanism therefor, and although an engine cylinder and its controlling valve mechanism, in accordance with this invention, is designed primarily for use in connection with steam driven engines of the reciprocating type, yet it is to be understood that it can be employed in connection with any class of power driven engines for which it is found applicable, and the invention has for its object to provide, in a manner as hereinafter set forth, an engine cylinder and its controlling valve mechanism so constructed and arranged relatively to each other that when employed for driving purposes will obtain increased engine power with a reduction in steam or other motive fluid consumption, as well as reducing the expansion of steam or other motive fluid to a minimum when supplied to the valve mechanism and from and to the engine cylinder, thereby obtaining substantially maximum efficiency of the steam or other motive fluid when acting on the piston in the engine cylinder, and further including means for expediting the exhaust of the steam or other motive fluid from the engine cylinder thereby providing for quick action of the piston in such cylinder when it is impacted upon by the incoming steam or other motive fluid which has had its maximum efficiency substantially retained.

Further objects of the invention are to provide a steam engine, in a manner as hereinafter set forth, and which is simple in its construction and arrangement, durable, strong, thoroughly efficient in its use, readily assembled and disassembled when occasion so requires, and comparatively inexpensive to set up.

With the foregoing and other objects in view, the invention consists of the novel construction, combination and arrangement of parts, as hereinafter more specifically described and illustrated in the accompanying drawings, wherein is shown an embodiment of the invention, but it is to be understood

that changes, variations and modifications can be resorted to which come within the scope of the claims hereunto appended.

In the drawings wherein like reference characters denote corresponding parts throughout the several views:—

Figure 1 is a top plan view of a steam or other motive fluid driven engine in accordance with this invention.

Figure 2 is a side elevation thereof.

Figure 3 is a longitudinal sectional view on line 3—3, Figure 4.

Figure 4 is a section on line 4—4, Figure 1.

Figure 5 is a grouped perspective view of the engine cylinder and its controlling valve mechanism.

Referring to the drawings in detail, 1 and 2 denote a pair of supports, and the former is employed for supporting the engine cylinder to be presently referred to and the latter provides bearings for the crank shaft 3. The support 2 is substantially U-shaped to provide a clearance for the operation of the crank 4 of the shaft 3. The shaft 3 carries a fly wheel 5 and a transmission pulley 6. Formed integral with the support 2 and extending towards the engine cylinder, which is referred to generally by the reference character 7, is a semi-cylindrical casing 8, having its free end provided with a circular disk 9 which is secured to one end of the engine cylinder 7 by hold-fast devices 22. Secured within the casing 8 is a pair of oppositely disposed track members 11, 12, which constitute guides for a cross head 13 to which the pitman 14 is pivotally connected and also to which is adjustably connected the piston rod 15, of the piston 16 which operates in the cylinder body 17. The bottom of the casing 8 is cut away, as at 18, to provide a clearance for the operation of the crank 4 and the end 19 of the pitman 14, which is connected to the crank 4.

The disk 9 forms a head for the cylinder body 17 and said disk 9 is provided with a circular offset 20 which extends into the cylinder body 17. The cylinder body is flanged, as at 21, and engaging thereagainst is the disk 9 which is also secured to the flange 21 by hold-fast devices 22. The circular offset 20, as well as the disk 9, is provided with a centrally disposed opening 23 for the passage of the piston rod 15, and said disk 9 has its outer face formed with

a tubular extension 24 constituting a bearing for the piston rod 15 and which is peripherally threaded for the reception of an apertured cap member 25 through which extends the rod 15. The cap member 25 is employed for maintaining a packing 26 against the tubular extension 24 and around the rod 15.

That end of the cylinder body 17 which is opposite the end provided with the flange 21, is formed with a flange 27 against which abuts a disk 28 which constitutes the other head of the cylinder 7, and said disk 28 is secured to the flange 27 by hold-fast devices 22. The inner face of the disk 28 is formed with a circular offset 29 which extends into the cylinder body 17. The circular offset 20 is formed with a bevelled cut-out portion 30, and the circular off-set 29 is formed with 20 a bevelled cut-out portion 31. The circular off-sets 20, 29, in connection with the cylinder body 17 form a piston chamber 32. The cut-out portions 30 and 31 are formed in one side of the edge of the circular off-sets 20, 29, and extend partly across the inner ends of the steam inlet channels 33, 34, which are disposed at an inclination and extend through one side of the cylinder body 17. The cut-out portion 30 associates 30 with the inlet channel 33 and the cut-out portion 31 associates with the inlet channel 34, and the bevelled walls of said cut-out portions constitute means for deflecting the in-coming steam or motive fluid into the piston chamber 32 at the ends thereof. The channel 33, as well as the channel 34 is also employed for exhausting the steam or motive fluid from the chamber 32, and the arrangement is such, that when the steam or motive fluid is supplied through the channel 33 it is exhausting through the channel 34, and when supplied through the channel 34 it is exhausting through the channel 33.

The cylinder body 17 at one side is formed 45 with a rectangular offset 35 through which extend the channels 33, 34, and these channels project towards each other and extend entirely through the offset 35 at an inclination. The offset 35 is formed with a series 50 of sockets 36, having threaded walls and which are employed for receiving the threaded ends 37 of securing bolts 38, and the purpose of the said bolts 38 will be presently referred to.

55 That side of the cylinder body 17, which is formed with the offset 35 is provided at each end with a pair of exhaust ports and the exhaust ports of one pair are indicated at 39 and the exhaust ports of the other pair are indicated at 40. The exhaust ports of one pair extend towards the exhaust ports of the other pair at an inclination and entirely through the offset 35. Preferably the exhaust ports of each pair are arranged 60 in superposed relation and the exhaust ports

of each pair are furthermore positioned inwardly with respect to an inlet channel in a manner so that the discharge ends of said ports will be positioned inwardly with respect to the inlet ends of the channels 33 and 34. The inclination of the ports 39 and 40 is greater than the inclination of the channels 33 and 34.

Positioned against the rectangular offset 35, is a valve housing 41, in the form of 75 a rectangular frame and with said frame provided with openings 42 which register with the sockets 36. Arranged against the housing 41, is a rectangular plate 43, having its inner face provided with a rectangular extension 44, which is positioned within the housing 41 and is of a thickness whereby it will not completely fill the opening formed by the housing 41. The extension 44 is channeled as at 45 and with 80 the channel extending the entire length of the inner face of the extension 44. That part of the inner face of the extension 44 which is not channeled, is indicated at 46, 47, and which provides a valve seat for a 85 reciprocatory valve to be presently referred to. The plate 43 is formed with openings 48 which register with the openings 42 in the housing 41, and through the openings 42, 48, extend the bolts 38 whereby the housing 90 41 and plate 43 are connected together and are further connected to the rectangular offset 35 of the cylinder body 17.

The plate 43, centrally thereof, is formed 95 with an opening 49, having a threaded wall, and with which engages a steam or other motive fluid supply pipe 50. The extension 44 is formed with a conoidal-shaped pocket 51 which registers with the opening 49, and leading from the pocket 51, is a conducting 100 channel 52 which is of materially less diameter than the opening 49 and which opens into the channel 45, and the latter constitutes what may be termed a steam or motive fluid inlet space.

110 Arranged within the housing 41 is a reciprocatory valve 53, which is of less length than the opening 54 formed by the frame which constitutes the housing 41. The valve 53 rides against the portions 46, 47 of the extension 44 which constitute the seat for the valve 53, and that face of the valve 53 which is mounted on its seat is continuous throughout and said face is used to confine the supplied steam or motive fluid in the 115 channel 45 in a manner whereby the steam will pass around one end or the other end of the valve 53 for the purpose of supplying the steam or other fluid in the channel 45 to the chamber 32 through the channel 33 or through the channel 34. The other face 120 of the valve 53 is positioned against the rectangular offset 35 and such face is formed with a pair of pockets 55, 56, which extend lengthwise of such face and with the pocket 125 130

56 arranged above the pocket 55. The pocket 56 is of less length than the length of the pocket 55 and with the latter extended from each end of the pocket 56, by setting up 5 the pocket 56 with respect to the pocket 55 in the manner as stated, in that face of the valve 53 in which is formed the pockets 55, 56, there is provided enlarged flattened portions 57, 58, which are employed for alternately 10 closing the ports 39 and 40. The pockets 55, 56, constitute what may be termed an exhaust steam or motive fluid receiving space and with the exhaust through a channel 33 or 34 discharging into the pocket 55 and 15 with the exhaust from the ports 39 or from the ports 40 discharging into the pocket 56.

The rectangular offset 35 has an angle-shaped exhaust channel 59, which includes a vertical and a horizontal leg and with the 20 horizontal leg communicating with the pocket 55 centrally thereof. Communicating with the vertical leg of the exhaust channel 59 is an exhaust pipe 60 which is secured to and depends from the rectangular offset 35.

25 The flattened portions 61, 62, of that face of the valve 53, which is provided with the pockets 55, 56, alternately close the inlet channels 33, 34.

The valve housing 41 has one end provided 30 with an opening through which extends a valve stem 63, which is secured to one end of the valve 53. The valve stem 63 is pivotally connected, as at 64, to an eccentric rod 65 which projects from an eccentric 66 carried 35 by the shaft 3, and such connection provides for the reciprocation of the valve 53 during the operation of the engine to provide for alternate supply and exhaust from the ends of the piston chamber 32.

40 The setting up of the narrow channel 45 in the manner as shown and which constitutes an inlet space for the motive fluid reduces the expansion of the steam or other motive fluid to a minimum as it is being supplied to the piston chamber 32, and under such conditions the pressure of the steam or motive fluid is maintained substantially normal when it acts upon the piston 16, and owing 45 to the employment of what may be termed six exhaust ports, three at each end of the cylinder 32, two of the three formed by a pair of ports 39 or 40 and the other one of the three provided by an inlet channel 33 or 34, an exhaust area materially greater than 50 an intake area is provided under such conditions, an unusually quick exhaust is had, which provides for the quick shifting of the piston by the in-coming steam or motive fluid and under such conditions it has been found 55 that the power of the engine is materially increased without an increase in motive fluid consumption, in fact the power of the engine is increased with a reduction of motive fluid consumption.

60 Although the preferred embodiment of the

invention is as described and illustrated, yet it is to be understood that changes in the details of construction can be had which will fall within the light of the invention as claimed.

70 What I claim is:—

1. In a motive fluid driven engine a piston cylinder provided near each end with a combined intake and exhaust channel and further provided at each end with a pair of exhaust ports, the outer ends of said channels positioned at a point in closer proximity to the ends of the cylinder than the outer ends of said ports, a reciprocatory valve for controlling supply and exhaust through said 75 channels and exhaust through said ports, said valve having one face provided with flattened portions for alternately closing the ports and channel at one end of the cylinder with respect to the ports and channel at the 80 other end of the cylinder, that face of said valve having the flattened portions being further provided with a pair of pockets of unequal length, the pocket of greater length opening said channels to exhaust and the 85 pocket of less length opening said ports to exhaust.

2. In a motive fluid driven engine a piston cylinder provided near each end with a combined intake and exhaust channel and further provided at each end with a pair of exhaust ports, the outer ends of said channels positioned at a point in closer proximity to the ends of the cylinder than the outer ends of said ports, said channel and ports at one 90 end of the cylinder inclining towards the channel and ports in the other end of the cylinder, a reciprocatory valve for controlling supply and exhaust through said 95 channels and exhaust through said ports, said valve having one face provided with flattened portions for alternately closing the ports and channel at one end of the cylinder with respect to the ports and channel at the 100 other end of the cylinder, that face of said valve having the flattened portions being further provided with a pair of pockets of unequal length, the pocket of greater length opening said channels to exhaust and the 105 pocket of less length opening said ports to 110 exhaust.

3. In a motive fluid driven engine a piston cylinder provided near each end with a combined intake and exhaust channel and further provided at each end with a pair 120 of exhaust ports, the outer ends of said channels positioned at a point in closer proximity to the ends of the cylinder than the outer ends of said ports, said channel and ports at one end of the cylinder inclining towards the channel and ports in the other end of the cylinder, the inclination of said 125 ports being greater than the inclination of said channels, a reciprocatory valve for controlling supply and exhaust through said 130

channels and exhaust through said ports, said valve having one face provided with flattened portions for alternately closing the ports and channel at one end of the cylinder with respect to the ports and channel at the other end of the cylinder, that face of said valve having the flattened portions being further provided with a pair of pockets of unequal length, the pocket of greater length opening said channels to exhaust and the pocket of less length opening said ports to exhaust.

4. In a motive fluid driven engine a piston cylinder provided near each end with a combined intake and exhaust channel and further provided at each end with a pair of exhaust ports, the outer ends of said channels positioned at a point in closer proximity to the ends of the cylinder than the outer ends of said ports, a reciprocatory valve for controlling supply and exhaust through said channels and exhaust through said ports, said valve having one face provided with flattened portions for alternately closing the ports and channel at one end of the cylinder with respect to the ports and channel at the other end of the cylinder, that face of said valve having the flattened portions being further provided with a pair of pockets of unequal length, the pocket of greater length opening said channels to exhaust and the pocket of less length opening said ports to exhaust, a valve housing secured to said cylinder and inclosing said valve, said valve of less length than the length of the housing, and a plate closing the outer side of said housing and provided with an extension constituting a seat for said valve, said extension formed with a lengthwise extending shallow channel constituting a motive fluid inlet space, said extension being of greater length than the length of said valve.

5. In a motive fluid driven engine a piston cylinder provided near each end with a combined intake and exhaust channel and further provided at each end with a pair of exhaust ports, the outer ends of said channels positioned at a point in closer proximity to the ends of the cylinder than the outer ends of said ports, said channel and ports at one end of the cylinder inclining towards the channel and ports in the other end of the cylinder, a reciprocatory valve for controlling supply and exhaust through said channels and exhaust through said ports, said valve having one face provided with flattened portions for alternately closing the ports and channel at one end of

the cylinder with respect to the ports and channel at the other end of the cylinder, that face of said valve having the flattened portions being further provided with a pair of pockets of unequal length, the pocket of greater length opening said channels to exhaust and the pocket of less length opening said ports to exhaust, a valve housing secured to said cylinder and inclosing said valve, said valve of less length than the length of the housing, and a plate closing the outer side of said housing and provided with an extension constituting a seat for said valve, said extension formed with a lengthwise extending shallow channel constituting a motive fluid inlet space, said extension being of greater length than the length of said valve.

6. In a motive fluid driven engine a piston cylinder provided near each end with a combined intake and exhaust channel and further provided at each end with a pair of exhaust ports, the outer ends of said channels positioned at a point in closer proximity to the ends of the cylinder than the outer ends of said ports, said channel and ports at one end of the cylinder inclining towards the channel and ports in the other end of the cylinder, the inclination of said ports being greater than the inclination of said channels, a reciprocatory valve for controlling supply and exhaust through said channels and exhaust through said ports, said valve having one face provided with flattened portions for alternately closing the ports and channel at one end of the cylinder with respect to the ports and channel at the other end of the cylinder, that face of said valve having the flattened portions being further provided with a pair of pockets of unequal length, the pocket of greater length opening said channels to exhaust and the pocket of less length opening said ports to exhaust, a valve housing secured to said cylinder and inclosing said valve, said valve of less length than the length of the housing, and a plate closing the outer side of said housing and provided with an extension constituting a seat for said valve, said extension formed with a lengthwise extending shallow channel constituting a motive fluid inlet space, said extension being of greater length than the length of said valve.

In testimony whereof, I affix my signature hereto.

HENRY O. WHITE.
